SOIL SAMPLING DEVICE

Henry Arthur Mohr, Waban, Mass., assignor to
 Raymond Concrete Pile Company, New York,
 N. Y., a corporation of New Jersey

Application October 28, 1938, Serial No. 237,382

10 Claims. (Cl. 255—1)

This invention pertains to a device for obtaining samples of soil at various depths below ground level. The present practice in obtaining samples is usually to drive a tubular casing to the desired depth; to remove the contents of the casing; to lower through the casing a pipe having on its lower end a sampling "spoon"; to drive the spoon into the soil by means of a drop weight on the upper end of the pipe; and then to withdraw the spoon with the soil sample within it.

Difficulty has been encountered in obtaining large samples except in soil having certain favorable physical properties, and then even at best the quality of the samples and success of the operation has been uncertain.

The difficulty arises not in getting the desired sample into the spoon, but in raising the spoon to ground level without losing part or all of its contents.

An object of the present invention is to provide the lower end of the spoon with a gate or valve adapted to permit a full diameter sample to enter the spoon, in combination with means for closing the gate to prevent loss of any part of the sample while the spoon is being raised to ground level.

Further and other objects and advantages will be apparent from the specification and claims, and from the accompanying drawings which illustrate what is now considered a preferred embodiment of the invention.

Figures 1 and 1A show the exterior of the spoon.

Figs. 2 and 2A are cross-sections on line 2—2 and 2A—2A of Figs. 1 and 1A, respectively.

Fig. 3 is an enlarged detail view of the lower part of Fig. 2A.

Fig. 4 is a cross-section on line 4—4 of Fig. 3.

Fig. 5 is a detail view on line 5—5 of Fig. 3.

Fig. 6 is a view similar to Fig. 3 with the parts in different positions during withdrawal of the spoon.

Fig. 7 is a view on line 7—7 of Fig. 6.

Fig. 8 is a detail view on line 8—8 of Fig. 7.

Referring to the drawings, 10 is the drive pipe attached to the head 12 of the spoon. Pipe 10 is provided with vent holes 14. Projecting downwardly from head 12 and attached thereto is the spoon shell 16. Inside shell 16 is a removable tubular lining, preferably comprising a number of short sections 18, 20, 22, 24 and 26. The sections are all of the same outside diameter but the inside diameter of each section is somewhat less than the inside of the section next above it, 55 for a purpose which will appear.

The lower end of shell 16 is thickened as at 28 and is internally threaded as at 30 for attachment of a ring-like drive shoe 32 having a readily replaceable cutting edge 34. The inside diameter of 34 is no greater than the inside diameter of 32 and controls the outside diameter of the sample.

The lower part of ring 32 is counterbored as at 36 (Fig. 6) to provide a circumferential recess in the inner wall of member 32. Within this recess are four gates 38 as indicated in the full lines of Fig. 3 and in the shaded areas of Fig. 4. Each gate is provided at its lower end with a pair of trunnions 40 about which the gate is adapted to swing inwardly and downwardly, as indicated by 18 the arrows 42 in Fig. 3. The gates are spaced from each other by arcuate spacers 44 in a circumferential groove 45 which also serves to accommodate trunnions 40. One spacer 44, as indicated at the lower left in Fig. 7, is in two 20 pieces 46, 48, each held in place by a screw 50 and there is a space 52 between 46 and 48 so that by removing a screw 50 the released block 46 or 48 may be moved circumferentially to permit moving spacers 44 circumferentially, thus providing clearance whereby any gate 38 may be removed and replaced.

With the above structure in mind it will be understood that when the spoon is driven into the ground it will be filled with a cylindrical 30 sample of soil, the diameter of which, when entering the spoon, is controlled by the inside diameter of cutter 34. When the driving operation is completed, the spoon will be full of soil and gates 38 will be in their home positions as 35 indicated by full lines in Fig. 3. The next step in the operation is to actuate the gates so that they will prevent the captured sample from dropping out of the spoon while the spoon is being raised to ground level. The gate operating 40 mechanism will now be described.

The gates are actuated by the operator on the ground by means of wires passing down and outside the spoon and around the gates within the spoon so that tension on the wires will swing the 45 gates downwardly on their trunnions 40.

The arrangement will be readily understood from Figs. 3 and 4. An annular recess 54 is provided in the inner wall 36 of shoe 32 and in that recess are two loops of wire passing behind all 50 gates 38. One wire is designated 56 and the other 58. The free ends of the loops are conducted to ground level through suitable passages and slots in member 32 and then through spaced-apart tubular guides 60 on the outside of the 55

spoon. When tension is applied to the wires by the operator, the loops will be drawn to the broken line position of Fig. 4, thus forcing gates 38 to their broken line positions of Fig. 3. With 5 most soils the gates in the position of Fig. 3 will prevent the sample above the gates from dropping from the spoon during its withdrawal, but if there should be any incipient downward movement of the sample, the gates will be moved 10 automatically to their horizontal position of Figs. 6 and 7, thus stopping all movement of the sample. At the same time the wire loops serve to cut off the sample. In practice, the gates are usually of rectangular shape, as illustrated in the 15 drawings, but if necessary, they may be made of different shapes in order to more completely close the opening.

To prevent a vacuum in the bore hole below the spoon while it is being withdrawn, the spoon 20 may be provided with vertical external strips such as 62, which, if the spoon be rotated during its withdrawal, will provide paths permitting fluid to pass from above the spoon downward into the bore hole below the spoon.

25 After head 12 is removed from the spoon, the sample is pushed out of the spoon. This removal operation is aided by the fact that the internal diameters of spoon liners 18-26, inclusive, increase from the bottom to the top of 30 the spoon. This helps to support the sample in the spoon, tends to prevent distortion of the sample as it slides up into the liners, and aids in the removal of the sample from the spoon.

It is to be understood that the invention is 35 not limited to the specific embodiment herein illustrated and described, but may be used in other ways without departure from its spirit as defined by the following claims:

I claim:

40 1. A device of the class described, comprising in combination, a spoon adapted for driving into the ground for obtaining a sample of soil, a circumferential recess within the lower end of said spoon, a plurality of gates normally within said recess, and means operable from ground level for swinging said gates inwardly from said recess, said gate swinging means comprising a concealed wire device located within said recess for engaging said gates and extending to ground level.

50 2. A device of the class described, comprising in combination, a spoon adapted for driving into the ground for obtaining a sample of soil, a circumferential recess within the lower end of said spoon, a plurality of gates normally within said recess, and actuating means for said gates, said actuating means comprising a wire loop surrounding said gates and means operable at ground level for contracting the diameter of said loop for swinging said gates inwardly from said recess.

60 3. A spoon adapted for driving into the ground

for obtaining a sample of soil comprising in combination, an outer tubular shell and an internal removable lining, said lining comprising disconnected sections having the same outside diameter with a variable inside diameter increasing from bottom to top.

4. A spoon adapted for driving into the ground for obtaining a sample of soil comprising in combination an outer tubular shell and an internal removable lining, said lining comprising a plurality of independent and disconnected tubular sections in abutting relation one above the other, each of said sections having the same outside diameter and an internal diameter less than the section immediately above it.

5. A device of the class described, comprising, in combination, a spoon adapted for driving into the ground for obtaining a sample of soil, means at the lower end of said spoon for supporting the sample when said means is in closed position, and means operable when said spoon is below ground level for first moving said first mentioned means to closed position and then cutting off the lower end of said sample.

6. A device of the class described, comprising, in combination, a spoon adapted for driving into the ground for obtaining a sample of soil, gate means at the lower end of said spoon for supporting the sample when said gate means is in closed position, and means engaging said gate means and operable from ground level for first moving said gate means to closed position and thereafter cutting off the lower end of said sample while said spoon is below ground level.

7. The invention set forth in claim 6 in which said cutting means comprises a wire device substantially as described.

8. A device of the class described, comprising in combination, a spoon adapted for driving into the ground for obtaining a sample of soil, gate means at the lower end of said spoon for supporting the sample when said gate means is in closed position, and means for actuating said gate means when said spoon is below ground level, said actuating means comprising a contractable wire loop which is also effective to cut off the lower end of said sample.

9. The invention set forth in claim 6 in which said cutting means comprises a wire device for cutting off the lower end of said sample with a shear cut.

10. A device of the class described, comprising in combination, a spoon adapted for driving into the ground for obtaining a sample of soil, a plurality of gates at the lower end of said spoon for supporting the sample when said gates are in closed position, and a wire device disconnected from but engaging all of said gates to move the same to closed position when said spoon is below ground level.
